COOLING APPARATUS

Ernest H. Panthofer, Milwaukee, Wis., assignor to Perfect Corporation, Milwaukee, Wis., a corporation of Wisconsin

Filed Sept. 28, 1960, Ser. No. 59,113

1 Claim. (Cl. 165-69)

This invention relates to heat transfer apparatus and particularly to a mounting structure for isolating excessive vibrations of the drive motor from the heat transfer core.

In heat transfer apparatus of the type contemplated herein, a liquid is circulated through a core having a large surface area, and air is forced through the core. These cores include a large number of tubes and fins which are subject to damage from unnecessary vibrations. Motor driven fans units which are used to circulate air through the core have been found to have inherent vibrations which are transmitted to the core through the mounting structure.

The primary object of this invention is to provide a mounting structure which insulates the motor vibrations from the heating or cooling core.

This is accomplished by supporting the motor in a mounting structure which is secured to the main support frame. The mounting structure has a small amount of resiliency to absorb some of the vibrations of the motor and at the same time maintain the motor in a relatively fixed position with respect to the core. It has also been found that the fan guard, which is made of a generally light flexible construction, amplifies the vibrations of the motor and also transmits them to the core. The guard has, therefore, been secured to the motor mount assembly in order to isolate the core from these vibrations.

Other objects and advantages will be pointed out in, or be apparent from, the specification and claims, as will obvious modifications of the single embodiment shown in the drawings, in which:

FIG. 1 is a perspective view of the heat transfer unit with the fan assembled; and

FIG. 2 is an exploded view of the assembly.

As seen in the drawings, the heat transfer unit includes a pair of parallel support members 10, 12 constituting the main support frame for the unit which is generally secured to a rigid structure such as the floor. A top tank 14 and a bottom tank 16 are secured to the support members with a core 18 made of steel, copper, aluminum, or the like, mounted between the tanks and sealed by gaskets 20. Liquid is circulated by a pump or other means (not shown) through the core by admitting the liquid through openings 22 in the top tank so that it flows through tubes 25 in the core and out through opening 24 in the bottom tank. The heat in the liquid is conducted to the fins 27 from the tubes and air is forced through the core to dissipate the heat from the tubes and fins.

Fan 26 driven by electric motor 28 is mounted within shroud 32 to deliver air to the central portion of the core. This shroud is made of light gauge material and is secured to the support members and encloses the rear of

the core. A front screen guard 34 is mounted on the tanks to protect the front of the core. The motor is clamped within split ring 36 in the mounting assembly and has a number of radially extending support members 38 secured to and equally spaced about the motor ring. Each support member includes an outer rod 37 and an inner rod 39 with the outer end 40 of the members being bent to fit into holes 42 in the support members. Rubber grommets can be positioned on the ends 40 of the rods to reduce any noise which may occur at the connection due to the vibrations of the motor.

A fan guard 46 having a central aperture 48 is secured to the split ring by rods 50 and has its outer curved end welded to the inner rods at 52. It can be seen that any vibration from the motor will be transmitted to the support members by the rods which are secured to the supporting structure. By also mounting the fan guard on the inner rods of the motor mounting assembly, any vibration which is set up in the fan guard will be isolated from the shroud and core.

Although but a single embodiment of the present invention has been illustrated and described, it will be apparent to those skilled in the art that various changes and modifications may be made therein without departing from the spirit of the invention or from the scope of the appended claim.

I claim:

A heat transfer unit comprising:
a pair of rigid spaced support members;
a core, a top tank and a bottom tank connected together to provide a liquid radiator unit, said unit rigidly mounted on said support members between said members;
a fan unit including an electric motor and a fan blade driven thereby, said fan unit mounted adjacent said radiator unit to circulate air through said core;
a resilient mounting means for mounting said fan unit adjacent said radiator unit, said resilient mounting means including four radially extending arms and a fan support member fastened thereto, said fan support member adapted to receive and support said electric motor, said four radially extending arms having their outer ends fastened to said support members at the top and bottom portions thereof; and
a fan guard having a central aperture mounted between said fan blade and said electric motor, said fan guard fastened to said fan support member and said arms so that any vibration which is set up in said fan guard will be isolated from said liquid radiator unit.
